LLP(57) **CLAIM**

We claim the ornamental design for a carrier for cell culture, as shown and described.

DESCRIPTION

FIG. 1 is a perspective view of a carrier for cell culture according to our new design.

FIG. 2 is a front view thereof;

FIG. 3 is a rear view thereof;

FIG. 4 is a left side view thereof;

FIG. 5 is a right side view thereof;

FIG. 6 is top view thereof; and,

FIG. 7 is bottom view thereof.

The broken lines are included for the purpose of illustrating unclaimed portions of the carrier for cell culture and form no part of the claimed design.
